UNITED STATES PATENT OFFICE.

CARL E. PETERSON, OF NEWARK, NEW JERSEY.

DESIGN FOR A SLIDE.

45,239.

Specification for Design.

Patented Feb. 10, 1914.

Application filed April 7, 1913. Serial No. 759,543. Term of patent 14 years.

To all whom it may concern:

Be it known that I, CARL E. PETERSON, a citizen of the United States, residing at Newark, county of Essex, and State of New Jersey, have invented a new, original, and ornamental Design for Slides, of which the following is a specification, reference being had to the accompanying drawing, forming part thereof.

Figure 1 is a face view of a slide show-

ing my new design. Fig. 2 is a bottom view. Fig. 3 is a perspective view.

I claim:

The ornamental design for a slide, as shown.

CARL E. PETERSON.

Witnesses:

Wm. H. CAMFIELD,
M. A. JOHNSON.
